G. O. BRADY

CASKET

Filed Oct. 4, 1920

Golden O. Brady,
INVENTOR.

J. A. Kennedy, Jr.
ATTORNEY.

UNITED STATES PATENT OFFICE.

GOLDEN O. BRADY, OF CRANE, OREGON.

CASKET.

Application filed October 4, 1920. Serial No. 414,562.

To all whom it may concern:

Be it known that I, GOLDEN O. BRADY, a citizen of the United States, residing at Crane, in the county of Harney and State of Oregon, have invented certain new and useful Improvements in Caskets; and I do hereby declare the following to be a full, clear, and exact description of the invention, such as will enable others skilled in the art 10 to which it appertains to make and use the same.

This invention relates to new and useful improvements in caskets and has for its primary object the provision of a device of the 15 above stated character which is constructed of aluminum so it will be extremely light in weight, rust and germ proof and which will be sanitary and aid in preserving the body contained therein by excluding vermin 20 and air.

Another object of this invention is the provision of a casket of the above stated character which will be simple, durable, and efficient, and which may be manufactured and 25 sold at a comparatively low cost.

With these and other objects in view as will become more apparent as the description proceeds, the invention consists in certain novel features of construction, combination, and arrangement of parts as will be hereinafter more fully described and claimed.

For a complete understanding of my invention, reference is to be had to the following 30 description and accompanying drawings, in which:—

Figure 1 is a side elevation of a casket constructed in accordance with my invention,

Figure 2 is a top plan view of the same,

Figure 3 is a sectional view illustrating the means of securing the lining within the body of the casket,

Figure 4 is a plan view illustrating a glass 45 inner cover.

Referring in detail to the drawings, the numeral 1 indicates a body of a casket including a bottom wall 2, side walls 3 and end walls 4. The side walls 3 are of a comparatively short length and are connected by diagonally extending walls 5 so as to render the body of an artistic configuration and one that will comfortably receive a

human body. The side, end and diagonal walls have formed on their upper edges connected and outwardly extending flanges 6 adapted to support a cover 7 which in outline is of a corresponding shape to the body and is detachably secured to the flanges 6 by fasteners or screws 8. The cover 7 is 60 adapted to tightly seat upon the flanges 6 so as to establish an air-tight connection between the body and the cover. The body and cover are constructed from aluminum so that the device will be extremely light in 65 weight, germ and rust-proof and by excluding air, the body contained in the casket will be preserved to a great extent and also vermin will be excluded from the interior of the casket. The walls of the body 1 have 70 formed therein an inwardly directed flange 9 disposed in a plane slightly below the flanges 6 and is provided with a series of perforations 10 so that the lining 11 placed within the body 1 may be sewed or otherwise 75 secured to said flange. The side walls 3 are provided with handles 12 so that the casket can be conveniently handled or carried.

If desired, a glass cover 13 of a shape corresponding to the outlines of the body 1 may 80 be used and placed upon the flange 9 so that the human body within the casket may be viewed when the cover 7 is removed, still preventing germs from escaping from the casket.

While I have shown and described the preferred embodiment of my invention, it will be understood that minor changes in construction, combination, and arrangement of parts may be made without departing from 90 the spirit and scope of the invention as claimed.

Having thus described my invention what I claim is:—

A casket having the container section provided with an interior flange integral therewith, a lining, said flange being perforated to facilitate passage of stitching therethrough to secure the lining thereto, a one-piece transparent panel adapted to rest on said flange and stitching prevented from lateral displacement by the surrounding wall of the section, said flange being located below the upper edge of said section a distance substantially equal to the thickness of 105 the panel, an outwardly directed flange at

the upper edge of the section and substantially in the same horizontal plane with the panel to reinforce the sections and serve as a seat for the cover, and a cover section disposed out of engagement with said panel and attachable to said seat having its inner wall extending inwardly and upwardly over the panel.

In testimony whereof I affix my signature in presence of three witnesses.

GOLDEN O. BRADY.
